GAS FUELED HOT AIR GENERATOR

Andrew J. Faucher, Arlington, Tex.

Application August 4, 1954, Serial No. 447,875

4 Claims. (Cl. 263—19)

This invention relates to gas fueled hot air generators and more particularly to such generators or furnaces especially suited for supplying heated air to cotton driers.

The principal object of the invention is to provide a hot air generator which is entirely automatic in its operation and has incorporated therein such safety features as to remove fire hazards, an important attribute especially when the apparatus is to be used in cotton gins for drying cotton, the safety features including a gas pressure regulator; automatic control valves responsive to temperature variation (moisture content) of the cotton to be dried, effective to distribute gas flow to burners according to such temperature variations; valve means responsive to suction in the drying system for extinguishing all burners when suction diminishes below a predetermined degree.

Still another object of the invention is to provide a hot air generator exceptionally suited to drying cotton which consists of a plurality of banks of gas burners, each bank being supplied with fuel through separate conduits having separate fuel control valves for control of fuel to selected banks of burners, the latter being provided with a manual and an electrically energized pilot. The generator is connected in the system of conduits so that suction created by a blower in the system will draw heat from the burners into the cotton drier of the system, which can be of any conventional design but in any case, the degree of heat supplied by the burners is automatically controlled by temperature responsive devices located in the conduits through which cotton enters and leaves the drier and which are electrically connected with the valves supplying fuel to the burners.

Yet another object of the invention is to provide a hot air generator installed in a cabinet having a side opposite the burners closed by doors of screen mesh or other foraminous material so that air may be drawn across the burners into the drier system by suction therein, yet precluding entrance of lint or other readily ignitable material which would create a fire hazard. Moreover, provision is made for gaining entrance to certain parts of the generator assembly in the cabinet for repair or replacement while the burners are operating without requiring the opening of the screen doors.

Other objects will appear as the description proceeds when considered with the annexed drawings, wherein:

Figure 1 is a front perspective view of a gas fueled hot air generator constructed according to the invention.

Figure 2 is an end elevational view thereof.

Figure 3 is a fragmentary rear elevational view of the cabinet showing the burner assembly and pilot tube in the conduit of the cabinet.

Figure 4 is a perspective view of one of the burners.

Figure 5 is a diagram of a suitable form of electrical wiring used in the generator, and

Figure 6 is a fragmentary diagram of a conduit system incorporating the hot air generator and a cotton drier on a small scale.

Continuing with a more detailed description of the

2

drawing, reference is primarily made to Figure 1 wherein numeral 10 denotes generally the cabinet in which the assembly is housed and 11, the connector to which is joined the suction conduit 10a, Figure 6 of the cotton drier 11a, which latter may constitute any suitable conventional design. The cabinet is of greater length than height or depth and is separated into a pair of upper, longitudinally aligned compartments A and B and a lower compartment C which is coextensive with both the upper compartments. The vertical partition 12 separates the compartments A and B and the horizontal partition 13 separates compartment A from compartment C. A door 14, which may be solid or of foraminous material, as shown, is hinged at 15 to one end of the cabinet so that entrance may be gained to compartment A without opening doors 16 and 17 which provide a closure for the front of the cabinet and which are also foraminous so that free passage of air through the cabinet is permitted. It will become apparent in the course of the description to follow that the doors 16 and 17 must remain closed during operation of the generator.

Entering the cabinet 10 through the end wall 18 thereof is a gas pipe 19 in which is incorporated a manually actuated valve 20 actuatable exteriorly of the cabinet. Interiorly of the cabinet is located a gas pressure regulator 21 of conventional manufacture. The gas inlet pipe 19 is connected to the regulator 21 on one side and a short pipe 22 is connected to the regulator opposite pipe 19 and to the pipe 22, in turn, is connected a T 23. Another short length of pipe 24 is connected at one end to the T 23 in alignment with pipe 22 and at its opposite end to an electrically operated control valve 25. A burner pipe 26 is connected at one end to the opposite side of the control valve 25 and has its opposite end closed by a cap 27.

Arranged vertically in the chambers B and C of the cabinet 10 is a front bank of burners 28. These burners are of identical construction and one is shown in detail in Figure 4. Each burner consists of a tapered leg portion 29, the lower or smallest end of which is flared at 30 and is formed with an angular flange 31 having diametrically opposed ears 32. An intermediate plate 33 has ears 34 having apertures matching the apertures in ears 32 so that screws 35 may be threaded therethrough to hold the plate 33 to the flange 31 and also to secure an outer plate 36 adjustably flush with plate 33. The plate 33 has a tubular extension 37 on its center which extends through a central opening in plate 36 and the latter plate is rotatable on the extension so that apertures 38 and 39 in the plates 33 and 36, respectively, may be relatively adjusted to vary the amount of air mixed with the gas entering the pipe 29 of the burner through the tubular extension 37.

The upper or largest end of the burner has an annular flange 40 formed on a right angular portion 41 thereof, the latter being formed into a threaded nipple 42. A coupling 43 is shown in dotted lines as being threaded onto the nipple 42. Cast integral with the right angular portion 41 of the burner is a pair of oppositely extending projections 44. By observing Figure 3 it will be seen that these projections, which extend from the sides of the burner bear against the inner surface of a horizontal rail 45 and to secure the burners in upright position relative to the rail 45, a small rectangular block or plate 47 is set against the confronting ends of projections 44 of adjacent burners and a bolt 48 is passed through the plate 47 and the rail 45 and a wing nut 49 is threaded onto the end of the bolt (Figure 1).

The rear bank of burners 28a is identical with the front bank of burners and are mounted in a manner identical to that in which the front burners are mounted, hence all of the elements of which both banks of burners

are composed bear the same characters of reference except that the horizontal rail from which the rear burners are supported is identified by numeral 50 in Figure 1. The rear bank of burners 28a is, however, elevated slightly above the front bank of burners, as shown, so that one will ignite the other.

Each burner 28 of the front bank is connected to the horizontal fuel pipe 26 by a short pipe 51, Figure 1, and each pipe 51 has incorporated therein a valve cock 52 for manually regulating or shutting off selected burners in the bank, when necessary or desired.

The burners 28a of the rear bank are supplied with gas through a horizontal pipe 53 to which each burner is connected by a short pipe 54, each having a regulating valve 55 incorporated therein. The fuel pipe 53 has one end communicating with one side of a control valve 56 and its opposite end sealed. The control valve 56 is identical to the control valve 25 in the fuel pipe supplying the front burners and to its opposite side is connected a pipe 57 which communicates with the T 23. Hence pressure of fuel to both banks of burners is controlled by the single regulator 21.

In order to compensate for the distance between the front burner assembly and the ignition points of the burners, each has a pipe extension 58 (Figure 3) screwed into the coupling 43 whose end terminates in the same plane with the ends of the couplings 43 of the rear bank of burners whose close adjacency to the rear wall of the cabinet 10 precludes necessity for pipe extensions such as the extensions 58 of the front burners.

Connected also to the regulating valve 21 by means of a small tube 59 (Figure 1) is a gas pressure regulator 60 which controls gas pressure to a pilot control valve 60a. A manual cut-off valve 61 is incorporated in the tube 59 for closing off fuel therethrough when necessary or desirable. A pressure gauge 62 is connected to one side of the regulator 60 and to the opposite side of valve 60a is connected a T 63, to one leg of which is connected a pipe 64 extending to an electrically energized pilot 65 (Figures 1, 3 and 5). A regulating valve 66 is incorporated in the pipe 64. Connected to the other leg of the T 63 is a similar pipe 67 which communicates with a manual pilot 68. This pipe also has incorporated therein a regulating valve 69.

The manual pilot 68 is in communication with a perforated distributing pipe 70 underlying the rear flush ends of the burners 28 and 28a as shown in Figure 3. The distributing pipe 70 has a series of perforations 71 which are smaller than adjacent perforations 72 which latter are made larger to accommodate the rear burners 28 which are on a higher plane than the burners of the front bank.

It has been stated that the invention is installed in the conduit system 10a of a cotton drier 11a. The fan or blower is indicated at 72a in Figure 6 but may be located at any suitable point in the conduit system of the drier 11a in order that the suction of the fan or blower of the system will draw air through the cabinet 10 and across the burner assemblies 28 by means of the connector 11 by which the generator is connected into the system. It is necessary that there be provided some means to insure that function of the burners depends upon suction through the generator. In other words, the burners will not operate unless the fan 72a is in operation. With this in view, an air switch 73 is provided which is in communication with a suction tube 74 by means of a smaller tube 75 (Figure 1), the suction tube 74 extending into the connector 11 of the cabinet 10 between the burners 28 and 28a and whose open end is disposed in the stream of air influenced across the burners by the said fan. The minus pressure created in the suction tube by movement of air thereacross is sufficient to actuate the air switch 73, thus to extinguish the burners in the manner to be presently explained.

Referring to the electrical system illustrated in Figure

5, it will be observed that a relay 76 of any suitable design is provided to which are connected the air switch 73; automatic pilot 65; pilot valve 60, burner valves 25 and 56; an ignition transformer 77 and a pair of thermostats or temperature control units 78 and 79.

The temperature control units 78 and 79 are located in the cotton ducts 10a and 12a (Fig. 6) through which cotton enters and leaves the drier. These temperature control units are of well known manufacture, one being arranged in the intake duct 10a of the cotton drier while the other is disposed in the cotton drier outlet duct 12a thereof, as indicated by reference numerals 78 and 79, respectively, in Fig. 6. The control units 78 and 79 may be substituted by moisture sensitive elements of well-known manufacture or such elements may function in conjunction with said control units in such manner that the moisture content as well as the temperature of the cotton will govern the action of the first and second stage valves, that is, the valves 25 and 56 which control flow of gas to the front and rear burner assemblies, respectively. For example, when the temperature of the cotton reaches 178° F., the temperature control 78 will cause valve 25 to close, thereby extinguishing the front burner assembly. An increase of 2° F., in the temperature of the cotton will cause the temperature control 79 to function to actuate the second stage valve 56, to extinguish the rear burner assembly.

In operation, the various regulator valves such as the master regulator 21; valves 52 and 55 of the burners 28; valves 61, 66 and 69 of the pilots 65 and 68 are all preset to predetermine the flow of fuel to the burners and pilots. The doors 16 and 17 of the cabinet are closed and the fan or blower 12a of the cotton drying system is started. Suction of the fan, causing a draft of air through the cabinet 10 and over the burners 28 will create a suction in the tube 74 in the duct connector 11 and which will actuate the air switch 73 to closed position. The main gas inlet valve 20 is opened and the fused disconnect 80 (Figure 5) is closed and after a period of one minute, the starting switch 81 is closed which energizes the electric pilot 65 through the relay 76 and ignition transformer 77.

A suitable type of electric pilot is found in the Minneapolis-Honeywell flame rectifier pilot which is shown in Figures 1, 3 and 5. Since the design and function of this pilot is conventional, a description thereof per se is not considered necessary. Gas supplied by the manual pilot 68 is ignited by the automatic pilot 65 which latter ignites both banks of burners. Air drawn through the cabinet 10 is heated by the burner assemblies 28 and 28a and conveyed to the cotton drier. As the cotton passes through the ducts leading to and from the drier, the temperature controls 78 and 79 function to vary the amount of fuel passing through the valves 25 and 56 according to the moisture content or temperature of the cotton, thus varying the degree of heat generated by the burner assemblies 28 and 28a. As stated previously, when the temperature of the cotton rises to a predetermined degree, valve 25 will be closed to extinguish the front bank of burners and a slight increase in temperature as indicated by the control 79, valve 56 will be closed to extinguish the companion bank of burners.

If, at any time the suction in the drying system should close or be interrupted for any reason, such as by the stoppage of the fan therein, the air switch 73 will automatically cause the closing of valves 25 and 56, thereby cutting off all fuel to the burner assemblies 28 and 28a, as well as to the manual pilot 68 through the medium of regulator 60 and valve 60a. This latter valve which is of conventional manufacture, is also made to close in the event the flame of the electrical pilot 65 is extinguished for any reason. In order to immediately determine whether or not the air switch 73 is functioning, a lamp 83 (Figure 5) is incorporated in the circuit

which is illuminated during closed position of the air switch.

In order to extinguish the burners 28 and 28a and electrical pilot 65 in a manner other than under emergency conditions, the switch 82 is actuated whose function in relation to the burner valves 25 and 56 is self-evident in the electrical diagram shown in Figure 5.

While the hot air generator has been described chiefly in association with a cotton drier, it is clearly apparent that it has ready application in other fields where heated air may be required, such as in the heating of buildings and many other adaptations.

Manifestly, the construction as shown and described is capable of some modification and such modification as may be construed to fall within the scope and meaning of the appended claims is also considered to be within the spirit and intent of the invention.

What is claimed is:

1. In combination with a duct through which air is constrained to pass, a hot air generator comprising a cabinet having an air passage in communication with said duct an air previous screen through which air is influenced into said air passage and duct and adapted to intercept inflammable particles entrained in said air, a gas fuel line entering said cabinet, a gas pressure regulator in said line, a front and a rear gas supply pipe disposed in longitudinal parallelism in said cabinet and communicating with said regulator, a series of longitudinally spaced and vertically disposed front burners communicating with said front pipe, a series of rear burners communicating with said rear pipe in parallelism with said front burners, said burners terminating in the same plane in the air passage of said cabinet, a manual pilot for said burners, an electric pilot, an electrical circuit, a control valve for each of said gas supply pipes and connected electrically in said circuit, remote temperature responsive means for actuating said control valves in accordance with changes in hot air requirements of said burners, an air switch in said circuit and means disposed in said air passage and communicating with said air switch to actuate the same upon cessation of air flow through said cabinet, to close said control valves to extinguish said burners.

2. In combination with an air duct through which air is passed, a hot air generator comprising a cabinet through which air passes into said air duct screens through which said air is passed preliminary to its passage into said duct to intercept inflammable particles entrained in said air, a first group of gas burners in said cabinet in the stream of air entering said air duct through said cabinet, a second group of burners forwardly of and adjacent said first group of burners, a manual pilot for said burners, an electric circuit, an electrically ignitable pilot in said circuit, an individual gas supply pipe for each of said groups of burners, a main gas supply pipe communicating with said individual gas supply pipes, a pressure regulator in said main supply pipe, a control valve in said circuit for each of said individual supply pipes, an air actuated switch in said circuit held in closed position by suction of air through said cabinet and across said burners, said air switch being effective, upon cessation of said suction to close said control valves, and temperature responsive means in said air duct and having electrical

connection with said control valves and said electrically ignitable pilot to vary the amount of fuel delivered thereto in accordance with temperature changes in said air duct.

3. Apparatus for generating hot air for delivery into a distributing duct having an air moving means therein, said apparatus comprising a cabinet connected to said distributing duct and through which air is drawn by the air moving means of said duct means through which said air is constrained to pass in its course to said distributing duct for removal therefrom of combustible materials entrained therein, gas burners disposed in the stream of air passing through said cabinet, a gas supply pipe for said burners, a pressure regulator in said gas supply pipe, an electric circuit, a gas control valve in said circuit and communicating with said gas supply line, a manual and an electrical pilot, the latter being connected in said circuit for igniting said manual pilot and said burners, an air switch in said circuit and held closed by suction created by air drawn through said cabinet by said air moving means, means connecting said air switch electrically with said gas control valve to close the latter upon cessation of said air moving means an air suction tube disposed in the air stream forwardly of said burner and connected to said air switch and in which suction is established and maintained by said air moving means of said air distributing duct to maintain closed position of said air switch, and means located in said distributing duct and responsive to changes in temperature in said duct to actuate said control valve and vary the gas flow to said burners according to temperature requirements in said distributing duct.

4. Apparatus for heating air in an air distributing duct having air moving means therein, said apparatus comprising a cabinet having means for connecting the same to said distributing duct and through which air is caused to be drawn into said duct by said air moving means screens through which said air is constrained to pass for the removal of combustibles entrained in said air, a series of gas burners located adjacent to said connecting means, a gas supply pipe for said burners, an electrical circuit, a gas control valve in said circuit and communicating with said supply pipe, temperature and moisture responsive means in said duct for actuating said control valve to supply gas to said burners in accordance with heat requirements in said duct, means for igniting said burners, an air switch in said circuit and connected with said control valve and means for actuating said air switch to close said control valve when air ceases to pass through the connecting means between said cabinet and said air distributing duct.
